O. M. ELLISON.
SPORTSMAN'S BOAT.
APPLICATION FILED APR. 17, 1915.

Patented Aug. 3, 1915.

UNITED STATES PATENT OFFICE.

OLEF M. ELLISON, OF CHICAGO, ILLINOIS.

SPORTSMAN'S BOAT.

1,148,961.

Specification of Letters Patent. Patented Aug. 3, 1915.

Application filed April 17, 1915. Serial No. 22,203.

To all whom it may concern:

Be it known that I, OLEF M. ELLISON, a citizen of the United States, and a resident of the city of Chicago, in the county of Cook and State of Illinois, have invented a certain new and useful Improvement in Sportsmen's Boats; and I do hereby declare that the following description of my said invention, taken in connection with the accompanying sheets of drawings, forms a full, clear, and exact specification, which will enable others skilled in the art to which it appertains to make and use the same.

My invention relates generally to improvements in sportsmen's boats and it consists, essentially, in the novel and peculiar combination of parts and details of construction, as hereinafter first fully set forth and described and then pointed out in the claims.

In the drawings which disclose the preferred mode of practising my invention, Figure 1, is a plan of my improved sportsman's boat. Fig. 2, is a side elevation thereof and Fig. 3 is an elevation of the boat, partly in section, separated into two sections and nested one into the other. Fig. 4 is an end elevation of one of the components of the boat. Fig. 5 is an elevation of the same as converted into a sportsman's tent. Fig. 6 is a horizontal section in line 6-6 of Fig. 2, showing rapid acting means for locking the bottoms of the sections of the boat together. Fig. 7 is an elevation of Fig. 6. Fig. 8 is a vertical section in line 8-8 of Fig. 1, disclosing the media of locking the tops of the sections of the boat together. Fig. 9 is an elevation of Fig. 8. Fig. 10 is a vertical section in line 10-10 of Fig. 1, showing means preventing inter-lateral movement of the sections of the boat when they are locked together. Fig. 11, is a vertical section in line 11-11 of Fig. 1, showing the manner of means devised to connect the ends of the boat when employed as a camp tent and the like. Fig. 12, is a plan of said means. Fig. 13 is a section in line 13-13 of Fig. 1, indicating a removable duffle box arranged in connection with one of said sections of my said invention. Fig. 14 is a vertical section of a removable support and its brackets employed as a hammock support when the boat serves the pur-

pose of a tent, and Fig. 15 is an elevation of one of said brackets.

Like parts are indicated by corresponding characters and symbols in all the figures of the drawings.

Reference is now made to the drawings in which S indicates the boat as a whole comprising the stem posts 10 and 10^a, the single full height side strakes 11 and 11^a, with their gunwales 12 and 12^a, and a longitudinally or laterally planked bottom B, the direction of planking as well as the type thereof (lap streak or carvel) being entirely a matter of choice, or the composite veneer structure may be used as desired. The bottom and sides are built over frames in the usual manner and calked, and then the steamed and bent ribs 13 are applied in a manner well known to those skilled in the art. The seams are now calked and the boat is complete as a typical sportsman's boat without the application of my invention. I now shape two bulkheads 14 and 14^a of the cross section of the boat at a point about four to six inches distant from the longitudinal center of the same and fit these bulkheads, while tightly clamped together, closely to the sides and bottom, and secure the same, each independently, to said sides and bottom by brass screws or copper clinch nails as the case may be. The fastening of these bulkheads receives particular attention and the work is thoroughly done, and the outer edge of each bulkhead is well calked at the side and bottom seams. There is now drilled or formed two sets of coinciding holes 15 and 15^a, either circular or of angular cross section, through both of said bulkheads. One set of these holes as at 15, Fig. 10, in bulkhead 14, is water tightly closed by plates 16, to preclude the entrance of water through said openings, and, into the companion holes in bulkhead 14^a, are driven pins 17, first covered with water proof glue or similar material, to make a water tight and immovable fit in the said companion holes, and it may be noted that these pins project beyond the outer face of bulkhead 14^a the thickness of bulkhead 14 and that they are adapted for a free fit in the openings 15 in said bulkhead. Along the upper edge of the bulkheads adjacent the sides 11 and 11^a of the boat are fixed double

hinged hasps 20 and staples 21 or equivalent means for clamping and holding together, in close contact, the bulkheads in a manner easily understood.

- 5 Along the lower ends of the outer faces of both the side strakes 11 and 11^a, in positions preferably equally distant longitudinally of the boat, in both directions from the bulkheads 14 and 14^a, are fastened angle brackets 25 and 25^a, the former adapted for the reception and oscillation therein of an eye-bolt 26, the opposite end of which is arranged to be received in a slot 27 in the perpendicular member 28, Fig. 6. At the free end of bolts 26 and eccentrically and pivotally secured thereto, are eccentric levers 29, which when in the position shown in Fig. 6 create a tension in rods 26 tending to draw the brackets 25 and 25^a closer together.
- 10 20 With all the devices placed in position on the boat, I take what is known as a "parting saw" and proceed to cut the boat into two parts of dissimilar length, the line of the cut being at the point C or at the facing faces 25 of the bulkheads 14 and 14^a. This sawing process completed, I plane the sawed edges to a smooth finish, and run a light strand of calking cotton at the outer seams 30, 31, 32, Fig. 4, of both bulkheads, whereupon I have 30 two square transom boats A and A', each of which is entirely independent of the other in every respect and yet joinable into a single craft by abutting the two boats, bulkhead to bulkhead, engaging the pins 17 into openings 15 and 15^a; applying the hasps and staples 20 and 21, and locking the lower edges thereof by the eccentric members 29.
- 35 Within the boat (or boats) are placed removable duffle boxes 33, 34, and 35, the box 40 34 of which may be employed as a rowing seat, though in most instances the craft will be used by camping chums, each possessed of a paddle and propelling the boat from bow and stern thereof. If, now, when on a 45 duck hunt, for instance, flocks of duck alight in two bayous, it requires only several seconds time to convert the craft into two hunting boats in a manner easily understood.
- The fact has been herein mentioned that 50 55 the two portions of the craft are of dissimilar length. This is for the purpose of enabling the section A' for instance to be nested into section A for ease of packing about, transportation and the like, the entire craft with its dunnage or duffle weighing only about 100 pounds for a boat the total length of which is sixteen feet.
- On the upper ends of the stem posts 10 and 10^a are fixed flag pole sockets 40 and 41, 60 the outer diameter of the latter being of a size to fit the interior of the former, whereby when the two halves A and A' are set up as a tent, Fig. 5, the socket 41 will fit the socket 40, and maintain the two sections A and A' in an upstanding A-shaped position.

In this position outside canvas flaps, shown in dotted lines at 50 in Fig. 5 may be employed to convert the structure into a snug A-tent, in the interior of which a hammock 51, or even two thereof may be supported by 70 removable transverse rods 52, engaging brackets 53 located in proper positions, as indicated in Figs. 5 and 2.

I have hereinbefore disclosed the preferred mode of practising my invention, but 75 I reserve the right to make such and any changes as might occur to one skilled in the art to which this invention appertains, or to make any and all such alterations as may be permitted under the doctrine of equivalents. 80

Having thus fully described my invention I claim as new, and desire to secure to myself by Letters Patent of the United States:—

1. A sportsman's boat comprising two sections, there being bulkheads contacting each other in the adjoining ends of said sections, fixed dowel pins in one of said bulkheads and corresponding water tight apertures receiving said dowel pins in the other of said 85 apertures, means on said bulkheads locking said bulkheads together and other means on the sides of said sections adjacent the bottoms thereof, likewise locking said sections.

2. A sportsman's boat comprising two sections, there being bulkheads contacting each other in the adjoining ends of said sections, fixed dowel pins in one of said bulkheads and corresponding water tight apertures receiving said dowel pins in the other of said 90 apertures, stirrups embracing the upper edges of said bulkheads, locking the same together, and means on the sides of said sections adjacent the bottoms thereof locking said sections together. 100

3. A sportsman's boat comprising two sections, there being bulkheads contacting each other in the adjoining ends of said sections, fixed dowel pins in one of said bulkheads and corresponding water tight apertures receiving said dowel pins in the other of said 110 bulkheads, means on said bulkheads locking said bulkheads together, and co-acting means located on said sections, on the sides thereof and adjacent the bottoms of said sections, 115 said means comprising brackets possessed of oscillatable studs having eccentric levers on their free ends, on one of said sections, and aligned members on the other of said sections, whereby upon oscillation of said levers, 120 said sections are locked together.

4. A sportsman's boat comprising two sections, there being bulkheads contacting each other in the adjoining ends of said sections, interfitting means in said bulkheads preventing independent lateral movement of said bulkheads and their sections, and co-acting and releasable eccentric means located on the exterior faces of the sides of 125 said sections, locking said sections together. 130

5. A sportsman's boat comprising two locked together but releasable sections, there being an upstanding post at the far end of one of said sections, and an upstanding interfitting socket at the far end of the other of said sections, whereby when said sections are

upstanding post is adapted to engage said interfitting socket.

In testimony that I claim the foregoing 10 as my invention, I have hereunto set my hand.

OLEF M. ELLISON.
